UNITED STATES PATENT OFFICE.

GEORGE C. KNAUFF, OF CHICAGO, ILLINOIS, ASSIGNOR TO EDMUNDS & JONES CORPORATION, OF DETROIT, MICHIGAN, A CORPORATION OF NEW YORK.

ELECTRIC FITTING.

1,260,400.

Specification of Letters Patent.

Patented Mar. 26, 1918.

Application filed February 18, 1917. Serial No. 148,936.

To all whom it may concern:

Be it known that I, GEORGE C. KNAUFF, citizen of the United States, residing at Chicago, in the county of Cook and State of Illinois, have invented certain new and useful Improvements in an Electric Fitting; and I do hereby declare the following to be a full, clear, and exact description of the invention, such as will enable others skilled 5 in the art to which it appertains to make and use the same.

My invention relates to electric sockets or connectors, its general objects being to provide an unusually simple and practical construction for a two-wire single-pole appliance of this kind. In electric fittings of this general class as used in connection with automobile lighting circuits, the space limitations within metal casings which are 10 proportionate in size to the lamps designed for this purpose make it difficult to insure good electrical connections with simple and inexpensive constructions. Thus, to accommodate the two wire terminals within the limited space, it is necessary to place both of 15 these out of alignment with the axial terminal required for contacting with the corresponding terminal on a lamp or a connector plug, so that an electrical connection 20 must be provided between the said axial socket terminal and one of the wire terminals. Such a connection is shown in U. S. Patent No. 1090629, issued to me March 17, 25 1914, in which I employ a spring-pressed 30 plunger for this purpose.

My present invention aims to simplify this construction by reducing the number of parts, and to improve the resulting electrical connections by entirely eliminating 40 one of the contact junctures required with the construction disclosed in my said issued patent. I accomplish this partly by making one of the wire-terminals integral with the axial socket terminal, or at least with 45 the casing of the latter, by equipping at least one of the adjacent insulating elements with a transverse recess, and otherwise after the general manner disclosed in the following specification and in the accompanying drawings, both of which will disclose further objects of my invention.

In the drawings,

Figure 1 is a central longitudinal section through a lamp-socket embodying my invention.

Fig. 2 is a transverse section, taken along the line 2—2 of Fig. 1.

Fig. 3 is an elevation of the main conducting element of the socket of Fig. 1.

Fig. 4 is an elevation of the same before 60 the offset is formed in it.

Fig. 5 is a central longitudinal section through a connector plug embodying my invention.

In employing my invention in a socket for 65 a so-called single-pole lamp (that is to say, one having a single terminal exposed on the end of its base, the other connection being made through the shells of the lamp and socket), I desirably use a substantially 70 cylindrical casing 1 equipped at one end with bayonet slots 2 for interlocking with pins 3 on the base of the lamp 4. Mounted within the casing 1 are two insulators 5 and 6 (of hard rubber or the like), the former 75 of which has a central bore partly housing a metal cylinder 7, which cylinder partly houses a spring-pressed contact plunger 8 adapted to engage the axial terminal 9 of the lamp. The companion insulator 6 is 80 equipped with two bores respectively housing two wire terminals 10 and 11, and also has at its inner end a transverse recess 12 adapted to connect one of the said bores with the axial bore of the insulator 5. This 85 transverse channel or recess houses a connecting element 14 for carrying the current from the wire terminal 10 to the plunger cylinder 7, and is preferably made integral with both of the latter. For this purpose I 90 first machine all three of the said elements in alignment with each other, as shown sectionally in Fig. 4. Then I form an offset in the portion 14 which is considerably 95 smaller in cross-section than the parts connected thereby, thus forming the portion W into a substantially Z-shaped connecting element. In assembling the socket, the forward insulator 5 may first be anchored in 100 the casing 1 by any suitable means, as by indenting lugs 22 into the said insulator. Then the composite conductor shown in Fig. 3 is slipped into its normal position, the rear insulator 6 is slid over this into place, the other wire terminal 11 is slid into position, 105 and finally both the latter terminal and the insulator 6 are anchored by inserting the screw 13 which electrically connects the wire terminal 11 with the casing of the socket. It will be obvious that by suitably 110

proportioning the depth of the recess 12 and the shape of the connecting element 14, this element will engage the rear wall of the recess, so that the said composite conductor 5 will require no auxiliary fastenings to hold the same in position.

However, my construction might be modified in many ways without departing from the spirit of my invention. For example, 10 Fig. 5 shows a connector plug in which the composite conducting element is held in operative position partly by the screw 15 which secures the wire 16 to the terminal 10, and also shows the forward insulator 5 as held 15 in place by the contracting of the forward end of a metal shell 17 grounded to the other terminal 11 by a screw 18.

In either case, it will be evident that my 20 construction obviates both spring contacts and other contact connections between the wire terminal 10 and the plunger cylinder 7, thereby reducing the required number of parts and insuring a good electrical connection between the said wire terminal and the 25 cylinder housing the plunger which contacts with the axial lamp terminal. In practice, I have found that offset bends of the types shown can readily be formed in turnings made of ordinary brass rod, hence 30 my construction also requires no departure in materials from those heretofore used for this class of goods.

I claim as my invention:

1. In an electric fitting, a casing, a pair 35 of insulating bodies mounted therein and equipped with relatively unlined bores extending longitudinally of the casing; and a

conducting member comprising in rigid formation a wire terminal and a plunger-cylinder housed respectively by the bores of 40 said bodies, and a connecting element extending substantially transversely of the casing and housed by one of said bodies.

2. In a fitting of the class described, a 45 conducting member comprising in integral formation a wire terminal, a contact terminal, and a substantially Z-shaped connecting element; a pair of insulators equipped with unlined bores respectively 50 slidably entered by the said wire terminal and contact terminal portions of the conducting member; a casing housing both of the insulators; and means associated with the casing for holding both insulators rigid within the casing.

3. In an electric fitting, a substantially cylindrical casing, a pair of insulating bodies mounted therein, and a conducting member carried jointly by said bodies; one of said bodies having a bore axial of the casing and the second body having a bore extending longitudinally of the casing but out of alignment with the axis of the latter, and one of said bodies having a recess connecting the said bores; the said member comprising 65 a contact portion housed by the said axial bore, a wire terminal portion housed by the other bore, and a connecting element rigid with both of the said portions and housed by the said recess.

Signed at Chicago, Illinois, February 12th, 1917.

GEORGE C. KNAUFF.
